UNITED STATES PATENT OFFICE.

BENJAMIN F. HARTWELL, OF WINCHESTER, MASSACHUSETTS.

BOOT OR SHOE, COMPOSITE SOLE THEREFOR, AND METHOD OF MANUFACTURING
SAME.

Application filed May 27, 1926. Serial No. 112,156.

My present invention relates to a novel and improved method of manufacturing boots and shoes, a composite sole for use therewith, and the boots and shoes made 5 thereby, and is a continuation in part of my prior and copending application Ser. No. 79,992, filed January 8, 1926.

In manufacturing boots and shoes, it is desirable to have a shoe structure with great 10 flexibility in the sole, combined with wear resisting qualities throughout, particularly at the toe. In carrying out my invention I may utilize any of the well-known types of 15 rubber or rubber-like compounds or compositions, including raw, crepe or latex rubber, or combinations of the same, to form a wear resisting and flexible layer of suitable thickness to constitute the outsole of the shoe. A 20 difficulty heretofore experienced in the use of crepe or latex rubber for outsoles, however, has been the tendency of this rubber to break away at the toe portion, becoming 25 ragged, exposing the otherwise concealed stitching, permitting the entrance of water to rot same, and the like disadvantages. In 30 order to overcome this difficulty, I provide one of the sole members of my novel composite sole, preferably the sole member provided for its toughness and relative rigidity, such as rubber fiber or the like composition, 35 although I may use leather or other materials if desired, with a reinforcing toe piece, preferably of the same material as the sole member of which it is a part or to which it 40 is secured. This toe piece, being tough and relatively rigid, withstands the wear at the toe of the shoe much better than the crepe rubber, and results in a longer lived, neater and more attractive shoe structure, not wear- 45 ing rough at the toe edges as does crepe rubber.

Furthermore, by utilizing my present novel details of construction, I am enabled to satisfactorily join crepe rubber and rubber 45 fiber or other rubber-like compositions, to form an outsole with the advantages of each, that is, with the wear resisting and tread qualities of crepe rubber, and the toughness and relative rigidity of the rubber fiber or 50 composition, coupled with the indestructibility of the solid toe piece and wear resistance of the same.

Further features of the invention, details

and advantages will be hereinafter more 55 fully pointed out and claimed.

Referring to the drawings, illustrating a preferred embodiment of my invention,

Fig. 1 is a side elevation of my invention applied to a welt shoe;

Fig. 2 is a bottom plan view of the same; 60

Fig. 3 is a cross-sectional view on the line 3—3 of Fig. 1;

Fig. 4 is a similar cross-sectional view 65 illustrating application to a McKay shoe;

Fig. 5 is a fragmentary detail of the toe portion with the toe piece as a separate unit instead of being integral with the rubber fiber or composition sole.

As shown in the drawings, my invention is 70 applied to a conventional shoe of the oxford type. 50 designates a usual shoe upper, with a welt 51 extending entirely around the shoe. To this welt 51 is secured, preferably by stitching, a sole member 52 of fiber, vulcanized rubber or other suitable material, such as leather or the like, and secured to the welt around its entire periphery. On the sole member 52, and preferably formed integral therewith, is a toe piece 53, beveled 75 at 54, as shown. Secured to the sole member 52 in any suitable manner, and prior to attachment to the welt, is a midsole 55, preferably of crepe rubber. This midsole 55 is attached to the sole member 52 throughout 80 its entire length rearwardly of the toe piece 53. With the composite sole thus described attached to the shoe, preferably by stitching 85 56, which extends through the toe piece 53 and through the midsole 55 and sole member 52 entirely and completely around the welt, an outsole 57, preferably of the same material as the midsole 55, is applied, and attached to the midsole 55 in any desirable 90 manner, preferably by coating the contacting 95 surfaces of the two crepe rubber sole members with a suitable solvent, such as benzol, and uniting the same under pressure, or heat and pressure, whereby a homogeneous, unified sole member is produced throughout the 100 entire length of the shoe, and no mechanical fastenings visible excepting at the toe piece 53, where the stitching is exposed. This outer sole 57 extends from the toe piece rearwardly to the end of the shoe, and may, and 105 preferably does, have a heel 58 formed in-

tegral therewith. One end of the outer sole 57 is beveled, so that in attaching the same to the midsole, this beveled end of the outer sole 57 under the beveled edge 54 of the toe piece forms a tight joint therewith, and one which will not be affected by the flexing of the sole in walking, and which will be firmly secured in position. In this present modification I have all the advantages of an entire sole and heel of crepe rubber, which are well known, together with the extremely advantageous feature of a solid toe piece of wear resisting material, and one which will stand the scuff and wear of walking, without pulling apart, as is liable to happen when the crepe rubber sole is carried to the full front of the shoe.

Figs. 3 and 4 illustrate in cross-sectional detail, the methods of attachment to welt 20 and McKay shoes respectively. In Fig. 3 is illustrated the member 50, insole 60 and welt 51, united by inseam stitching 61, with the sole member 52 and midsole 55 secured to the welt by welt stitching 56, which welt 25 stitching is carried completely around and through the toe piece 53. The outer or tread sole 57 is also shown in position to be attached to the midsole 55.

Fig. 4 illustrates the member 70 of a McKay shoe, having an insole 71, both united to the sole member 52 and midsole 55 by through and through stitching 72, and also shows the outer or tread sole member 57 in position for attachment as above described.

Fig. 5 illustrates, in fragmentary detail, the toe piece 53 as a separate unit, secured to the sole member 52 in any desired way, as by first cementing the same, and afterwards by the stitching 56 uniting the composite sole to the welt 51.

The importance and advantages of the shoe construction, and novel composite sole as above described, will be readily apparent to those skilled in the art, as will the advantages of composite soles, with

the strength and relative rigidity of a rubber fiber, vulcanized rubber, or composition sole, and the resiliency and flexibility of the crepe rubber on the tread surface, coupled with the indestructibility of the toe piece 50 and wear resistance of the same.

My invention is further described and defined in the form of claims as follows:

1. A composite sole, comprising a layer of rubber or rubber composition having a 55 beveled reinforcing toe piece, a relatively thin midsole of crepe rubber adhered to said layer, and a crepe rubber outsole unified with said crepe rubber midsole, one end of the outsole being beveled to cooperate with the 60 beveled end of the toe piece.

2. A composite sole, comprising a layer of rubber or rubber composition, a beveled toe piece attached thereto, a relatively thin midsole of crepe rubber adhered to said layer, 65 and a crepe rubber outsole unified with said crepe rubber midsole, one end of the outsole being beveled to cooperate with the beveled end of the toe piece.

3. The improved process of making boots 70 and shoes which consists in first assembling an insole and upper materials on a last, last- 75 ing the shoe, then applying a midsole of crepe rubber to a layer of rubber or rubber composition having a reinforcing toe piece, 80 which is bevelled inwardly at its rearmost edge, attaching this composite sole to the shoe by mechanical fastening means entirely around the periphery of the composite sole, then beveling an outsole of crepe rubber with 85 a unitary heel thereon, and adhering the outsole to the midsole, with the beveled faces of the toe piece and crepe rubber outsole co-operating to form a strong even joint, said outsole concealing and protecting the mechanical fastenings in the midsole, removing the last and completing the shoe.

In testimony whereof, I have signed my name to this specification.

BENJAMIN F. HARTWELL.
